UNITED STATES PATENT OFFICE.

GEORGE W. BROOKS, OF TOPEKA, KANSAS.

PRESSED-STEEL WINDOW SILL.

Application filed January 6, 1922. Serial No. 527,306.

To all whom it may concern:

Be it known that I, GEORGE W. BROOKS, a citizen of the United States, residing at Topeka, in the county of Shawnee and State 5 of Kansas, have invented certain new and useful Improvements in Pressed-Steel Window Sills, of which the following is a specification.

This invention relates to certain new and 10 useful improvements in window-sills of that general class formed of metal as a substitute for stone, cement or wooden sills, and it has for its objects among others to provide a simple, cheap, durable and efficient window-sill, preferably, although not necessarily, of pressed steel, constructed and shaped to fill the same space as previously occupied by the stone or other form of sill, and at the same time adapted to permit of 15 the passage of fresh air through the sill into the room where it may be delivered to any desired point, as directly above the radiator, or wherever it may be found most expedient.

20 The sill is preferably equipped with a controlling device, and means for preventing the ingress of flies and insects. The ventilation section may occupy a greater or less length of the sill, and the sill may be cut 25 in sections with joints coming under the mullions in the window opening. Where more than one window is used, the ventilating apparatus may be set in one or all sections of the sill, and the same may be closed all or 30 part of the time, as may be desired. The construction may be such that fresh air may be conducted from the ventilating sill into the floor or through the floor to the ceiling of the room underneath the said floor.

35 In fact, the invention is capable of embodiment in a variety of forms, some of the preferred ones only of which are herein 40 illustrated.

Other objects and advantages of the invention will hereinafter appear and the novel features thereof will be particularly pointed out in the appended claims.

The invention, in such preferred forms, is clearly illustrated in the accompanying 45 drawings, which, with the numerals of reference marked thereon, form a part of this specification, and in which

Figure 1 is a vertical section showing one of my improved sills with the outlet just above the base of the room. 55

Figure 2 is a vertical section showing a 45° outlet.

Figure 3 is a similar view, showing a modified form of outlet.

Figure 4 is an enlarged elevation of the 60 exterior of a window, showing the air inlet openings.

Figure 5 is a section on the line 5—5 of Figure 4, looking in the direction of the 65 arrows.

Figure 6 is a perspective detail of one end of a sill section and a gasket.

Figure 7 is a perspective view of the sill looking at the exterior.

Like numerals of reference indicate like 70 parts throughout the different views.

Referring to the drawings, 1 designates the sill, as a whole, in all of its forms, it being understood that the primary object is to insure a supply of fresh 75 air into the room.

It is well known that the unhealthy condition of foul air in congested or close quarters, such as sleeping compartments on trains or other places where bodies congregate, is harmful and injurious. 80

This new and useful method of ventilating gives a sufficient quantity of fresh air in crowded and often-used rooms, in stationary meeting places, as well as when traveling on 85 trains and the like, allowing the windows to be closed, fastened or securely locked by standard methods, meanwhile permitting a supply of fresh air into any place desired. The ventilator sill can be used for a sill 90 course or as a substitute for terra cotta, stone, etc.

It provides a neat and efficient method of ventilating.

It is slightly, artistic, and convenient of 95 access. The natural place or location for ventilation is at the window opening, or elsewhere, if desired. Ventilation can extend the full width of sill or a small section can be ventilated.

Regulation of the quantity of air used can be had mechanically or can be thermostatically controlled. Any known building material, particularly any gauge of metal, may 100

be used in the construction of this ventilated sill.

The sill and its appurtenances are built into the masonry or structure and become an integral part of the building. It can be made in standard sections and fastened together. When apparatus is used at the window, a bearing plate can be applied at each end or a panel can be formed on the surface of the sill.

It can be made weather-proof by any of the well-known methods of weather-proofing. Comparatively a light weight apparatus, it is easy to handle and install. It reduces cost of transportation. It is everlasting and non-breakable.

It can be used with or without ventilation attachment. Various designs of ventilator on the sill can be used for ornamental effects.

20 The ventilation louver and valve or damper, as shown, to the vent outlet in the room is a standard type of grille and damper which may be of any make damper as sold on the market at the present time, and I 25 will have it understood that I do not confine my invention to any particular form of interior grille or damper and device for controlling the air into the room as my invention relates more particularly to the sill 30 and appearance from the exterior, hence the details of construction of interior ventilating grille and damper control are immaterial.

In all of the forms the main portion of 35 the sill is rolled or shaped to the same form as the stone sill, having a lug 2 forming a weather bar located in a recess 3 in the wood sill 4, and having an upwardly inclined in-turned member 5, which as shown clearly 40 in Figures 1, 2 and 3, extends upward and inward into the space 6 between the courses of stone 7, where, if desired, it may be embedded in the mortar joint. This main section has its upper surface inclined, as seen 45 at 8, to form a sloping window stool. The inclined member 5, at its lower end, is provided with one or more openings 9 bored from the under side into the tapered channel, as clearly shown in Figure 1, so that 50 any moisture or condensation reaching the inside of the sill through the perforations 10 in the front face thereof, will immediately drain off through such openings. Furthermore, the drip thus formed constitutes 55 the correct water drip, as usually required in stone sills.

The interior hollow space 11 formed by the hollow member 12 constitutes the vent duct, this member being formed preferably 60 of galvanized iron to withstand the elements, but not to carry load, as all load from the window sill is carried down between the vents. The outer end 13 of this vent section 12 is designed to be covered 65 by hardware wire, cloth, copper fly screen-

ing, or the like 14 to prevent flies or insects passing through the duct into the interior of the room.

The ends of the sill are to be rolled and bent down at an angle of 90°, as seen at 15, 70 with about a two inch projection and to be welded at the corners, and provided with holes 16, as shown, for the reception of bolts 17 whereby the sections may be bolted together. Gaskets 18, of lead or other suitable material, about one-sixteenth of an inch in thickness, as seen in Figure 6, and provided with holes 19 for the passage of the bolts, are disposed between adjacent flanges of the sections, being preferably 75 coated with suitable material, as white lead putty, before the bolts are drawn tight so as to make the joint thoroughly waterproof.

The sill is usually supplied with one coat 85 of paint at the factory, and can afterwards be painted to match any color of trim either in stone or terra cotta.

The socket or recess 3 in the under side 90 of the wood sill which receives the upturned member 2 should be calked with waterproof cement or the like.

The shape and angle of the vent outlet may vary to suit varying conditions or wishes of the builder. For instance, in Figure 2 it is shown as extended at an angle of about 45° and its inclined end 20 is provided with a reticulated closure 21, while in Figure 3 the outlet extends inclinedly, as at 22, and thence horizontally, as at 23, and 100 is provided with the vertical closure 24 having suitable openings, as seen at 25. So the vent outlet may be made to suit varying conditions. In Figure 1 it is shown as terminating in a downwardly-extended duct 26 105 opening laterally into the room adjacent the base-board and provided with a closure 27 having openings 28.

In all instances the outlet end of the duct is controlled by a suitable valve or damper, 110 as shown, whereby the admission of air into the room may be regulated or cut off entirely. For this purpose I have shown in the present instance a member 29 pivoted in any suitable manner, at 30, and adapted 115 to be operated when desired by means of a control wheel 31, as indicated in Figures 1, 2 and 3.

At the left in Figure 4 the end of the sill is shown as built into the masonry work. 120 This sill is to project four inches out into masonry work from edge of the window opening. The end of this sill is to be turned back at a ninety degree angle and to have welded corners, the turned back surface to 125 run at least two inches in to the wall. 32 is a cast iron lug laid on top of the sill and attached with two countersunk screws 33, the same covered back under masonry wall. This lug provides the ordinary built up lug 130

as used with stone sills. This lug may or may not be used with sill as the space required for same may be taken up in a mortared joint.

5 From the foregoing it will be evident that I have devised a metallic ventilating sill that will fill all the requirements, and one that can be manufactured at comparatively small cost, as well as requiring unskilled 10 labor to assemble and put in place, and while the structural embodiment of my invention as hereinbefore described is what I, at the present time, consider preferable, it is evident that the same is subject to 15 changes, variations and modifications in details of construction, proportion of parts, etc., without departing from the spirit of the invention or sacrificing any of its advantages. I, therefore, do not intend to 20 strict myself to the exact construction, arrangement and proportion of parts, as hereinbefore disclosed, but reserve the right to 25 make such changes, variations and modifications as come properly within the scope of the protection prayed.

What is claimed as new is:—

1. A metallic window sill having an air vent with a register and a controlling means. 2. A metallic window sill having perforations, and a vent duct to receive the air admitted through said perforations, and means for controlling the egress of air from said duct. 3. A metallic window sill having perforations, and a vent duct to receive the air ad-

mitted through said perforations, and means for controlling the egress of air from said duct, the exit from the duct being disposed at an angle to the length of the duct.

4. A main section of a metallic window sill provided with a lug at the end to form a level base for the starting of masonry. 40

5. A pressed steel window sill embodying a main section with an upturned lug to form a weather bar, and a lug at the end to form 45 a level bar for the starting of masonry.

6. A pressed steel window sill embodying a main section with an upturned lug to form a weather bar, a lug at the end to form a level bar for the starting of masonry, and 50 a drip at the lower end.

7. A pressed steel window sill embodying a main section with an upturned lug to form a weather bar, a lug at the end to form a level bar for the starting of masonry, said 55 section having perforations for the ingress of air.

8. A pressed steel window sill embodying a main section with an upturned lug to form a weather bar, a lug at the end to 60 form a level bar for the starting of masonry, said section having perforations for the ingress of air, and an upturned lower end with drain openings.

9. A pressed steel window sill embodying 65 a main section with air inlet openings, and a cooperating vent duct having a perforated outlet, and controlling means therefor.

In testimony whereof I affix my signature.
GEORGE W. BROOKS.
